CIRCUIT CLOSER

Filed Dec. 14, 1927

Francis Marion Jacob ^{Inventor}
By Vernon E. Hodges ^{his} _{Attorney}

UNITED STATES PATENT OFFICE

FRANCIS MARION JACOB, OF COLUMBUS, MISSISSIPPI

CIRCUIT CLOSER

Original application filed March 22, 1927, Serial No. 177,446. Divided and this application filed December 14, 1927. Serial No. 239,819.

This invention relates to an improvement in circuit-closers, and is a division of my co-pending application Serial No. 177,446, filed March 22, 1927.

5 The object of the invention is to provide an electric circuit-closer, especially adapted for use in an automatic fire-alarm circuit that upon release it will automatically close the circuit through the alarm system. This permits of providing thermally controlled means for normally holding the circuit open; but should a fire occur in the proximity of said means, it will release the controlling arm of the circuit closer to allow an automatic closing of the circuit through the alarm system.

In the accompanying drawings:

Fig. 1 is an inner face view of the invention;

Fig. 2 is a transverse sectional view thereof; and

Fig. 3 is a front face view thereof.

This circuit-closer is adapted for use in connection with an suitable form of alarm apparatus and for closing an electrical circuit therethrough. A casing 1, which may enclose or support said apparatus, as desired, has a plate 2 secured thereto, as shown in the drawings, by means of the screws 3. Supported between the ears 4 formed on this plate, and pivoted thereto, as at 5, is a lever 6. The free end of this lever is provided with an opening 7, to which suitable actuating means, as for instance a cord (not shown) may be attached for normally tending to move the lever in one direction about its pivot 5. The opposite end of the lever 6 is engaged by a pin 8 provided with a collar 9 formed thereon, and housed within a sleeve 10 formed on the inner surface of the plate 2. The collar 9 is engaged by means of an expansion spring 11, which is interposed between said collar and a screw 12 screwed into the inner end of the sleeve 10 for adjusting the tension of the spring against the pin 8. This spring 11 normally tends to push the pin 8 outward to rock the lever 6 on its pivot 5.

On the opposite side of the pivot 5 from the pin 8, and slidably mounted in the plate 2, is a switch-pin 13 normally pressed outward against the lever 6 by a spring 14, which

is introduced between the head of this pin 13 and the face of the plate 2. The inner end of the switch pin 13 has a switch-arm 15 fixed thereto which extends vertically above and below it, as shown in Figs. 1 and 2. A plug 17 formed of insulating material is fixed in position in the plate 2 and carries metallic contact-strips 18 at its upper and lower ends in position to be engaged by the switch-arm 15 when the switch-pin 13 is pressed inward by the lever 6.

A connecting spring clamp 19 is fixed to the inner end of the switch-pin 13 and the plate 15, and similar connecting members 20 are fixed to the contact-strips 18. Suitable electrical conducting wires may be attached to these spring-conducting members 19 and 20, between which it is desired to make or break the electrical circuit, and these wires may lead to any suitable mechanism, as for instance to a fire-alarm circuit. The spring 14 is of less resiliency than the spring 11, so that when the lower end of the lever 6 is released, the spring 11 will move the lever 6 to push the switch-pin 13 inward against the tension of the spring 14 which moves the switch-arm 15 into bridging contact with the cross-strips 18. This mechanism closes the circuit between the connecting-member 19 and the electrical wire connected therewith, and the wires connected to the connecting members 20 through the medium of the switch-arm 15.

Whenever the lower end of the lever 6 is pulled outward, this forces the plunger 9 backward in the sleeve 10 against the tension of the spring 11 and releases the pressure on the switch-pin 13, allowing the spring 14 to force said pin outward through the plate 2, which carries the switch-arm 15 out of bridging engagement with the contact strips 18 and against the insulating plug 17 which breaks the electrical circuit between the wires connected to the clamps 19 and 20.

In this way, an automatic means is provided for automatically making the circuit upon release of the controlling-arm 6, as when a cord attached thereto with fusible means therein has become severed, thereby automatically closing the circuit to actuate

the fire-alarm or other mechanism in connection with which the electric switch may be used. The construction is simple, but very effective for the purpose accomplished, and may be adjusted to take care of varying lengths of cords or other attachments for the lever 6, and to obtain the proper automatic actuation of the switch.

I claim:

10. 1. A circuit-closer for a device of the character described, including a plate having a sleeve thereon, a lever pivotally mounted on the plate, a pin slidably mounted in the plate and having an end thereof in position to engage and actuate the lever, the opposite end of said pin extending into the sleeve, a spring mounted in the sleeve for normally tending to force said pin outwardly, means for adjusting the tension of said spring, and a switch-arm carried by the plate and operatively connected with the lever for actuation thereby.
15. 2. A circuit-closer for a device of the character described, including a plate having a sleeve thereon, a lever pivotally mounted on the plate, a pin slidably mounted in the plate and having an end thereof in position to engage and actuate the lever, the opposite end of said pin extending into the sleeve, a spring mounted in the sleeve for normally tending to force said pin outwardly, means for adjusting the tension of said spring, an insulated block carried by the plate having contacts thereon, a switch-arm in position to engage said contacts, and a spring-pressed switch-pin connected with said arm and slidably mounted through the plate in position to engage the lever on the opposite side of its pivotal point from the first-mentioned pin
20. 30. 35. 40. 45. 50. 55. 60. 4. A circuit closer of the character described including a support, a lever pivotally mounted thereon, a plunger in position to actuate the lever, resilient means for actuating said plunger, circuit breaking means associated with the lever, a pin connected with the circuit breaking means, and extending into operative relation with the lever, and resilient means of less resiliency than the first-mentioned resilient means normally tending to move the pin and lever against the action of said first-mentioned resilient means.

In testimony whereof I affix my signature.
FRANCIS MARION JACOB.
